Primary Examiner — Patricia A Palasik*(74) Attorney, Agent, or Firm* — Novick, Kim & Lee, PLLC; Jae Youn Kim; Hyun Woo Shin(57) **CLAIM**

We claim, the ornamental design for a cable laying apparatus, as shown and described.

DESCRIPTION

FIG. 1 is a perspective view of a cable laying apparatus, showing our new design and partially enlarged portions of the cable laying apparatus;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof;

FIG. 8 is an enlarged detailed view of the cable laying apparatus as shown in circle 8 in FIG. 1; and,

FIG. 9 is an enlarged detailed view of the cable laying apparatus as shown in circle 9 in FIG. 1.
